SPECIFICATION forming part of Design No. 19,014, dated April 9, 1889.

Application filed March 7, 1889. Serial No. 302,346. Term of patent 3½ years.

To all whom it may concern:

Be it known that I, JAMES L. FOLSOM, a citizen of the United States, residing in Brooklyn, county of Kings, and State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of a body, A, and a border, B. The body A is made up of large conventionalized flower forms or leaf and flower clusters, with here and there a large 20 leaf form scroll-shaped in character. The bor-

der B has a central rose-shaped form surrounded for the most part with large scroll-shaped leaf forms. On either side of this central figure are leaf clusters. The inner margin and the outer margin of the border are 25 ornamented with small scroll forms.

What I claim as new, and desire to secure by Letters Patent, is—

1. The design for a carpet, consisting of the body A, substantially as shown. 30
2. The design for a carpet, consisting of the border B, substantially as shown.
3. The design for a carpet, consisting of the body A and the border B, substantially as shown.
